United States Patent Office.

JAMES M. BENT, OF WAYLAND, MASSACHUSETTS.

Letters Patent No. 74,745, dated February 25, 1868.

IMPROVEMENT IN SHOE-NAILS.

The Schedule referred to in these Letters Patent and making part of the same.

Be it known that I, JAMES M. BENT, of Wayland, in the State of Massachusetts, have invented a new and useful Improvement in Nails for Boots and Shoes, of which the following, with the drawings, is a description.

My invention consists simply in constructing the nail with a conical or countersunk head, and its value consists in its capacity of being driven so as to countersink the head below the surface of the leather, and so allow of a finishing over the nail; and also of its wearing down to the shank without entirely wearing off the head, and without destroying or essentially diminishing its holding-power. The drawing shows the form of the nail.

The head of the nail, instead of being flat on both under and upper sides, is flat only on the upper side, and from thence is essentially conical or pyramidal, base upward, and diminishing downward to the shank part, which may be longer or shorter, as desired, for different kinds of work.

I am informed that counter-clout nails have been made which "have countersinks under their heads, and chisel points." My shoe-nail differs from these in shape, and is used for a different purpose. Cutting off the head of a counter-clout nail will not make of it what is known as a shoe-nail, and putting a conical head to an ordinary shoe-nail will not make of it a counter-clout nail. My nail is an invention of my own. I could find nothing like it in use anywhere. I could not find it at nail-makers' or hardware shops, or shoemakers' or finders'. I was compelled to get such as I wanted made expressly for me, upon my description and order. From my using them, and from that alone, other shoemakers have begun to use them, deriving their knowledge entirely from my invention and introduction of the article. My nail is unlike a counter-clout nail, and, as I verily believe, was never known or used before I invented it. It is an ordinary headless cut shoe-nail, combined with a conical head, having two sides, from the root of the head to the end, tapering, and two sides parallel, and the end blunted.

What I claim, therefore, as a new article of manufacture, is—

The cut shoe-nail, with conical head, and tapering and parallel sides, as described.

In testimony whereof, I have hereunto subscribed my name.

JAMES M. BENT.
